UNITED STATES PATENT OFFICE

124,014

DESIGN FOR BUILDING SIDING PANEL

Abbott Coburn, Chicago, Ill.

Application January 2, 1940, Serial No. 89,266

Term of patent 14 years

To all whom it may concern:

Be it known that I, Abbott Coburn, a citizen of the United States of America, residing at Chicago, in the county of Cook and State of Illinois, have invented a new, original, and ornamental Design for Building Siding Panel, of which the following is a specification, reference being had to the accompanying drawing, forming a part thereof, in which:

Fig. 1 is a perspective view of a building siding panel showing my new design; and

Fig. 2 is a sectional view thereof taken on line 2—2 of Fig. 1.

The essential feature of my design consists in providing simulated mortar grooves on a panel of the type shown to give the effect of being constructed of various sized rectangular ashlar stones, with end concentrations of small ashlar, differing in length and varying in height, and a plurality of large ashlar of varying sizes in the central portion, all arranged substantially as shown.

What I claim is:

The ornamental design for building siding panel, as shown and described.

ABBOTT COBURN.
